HAIR CURLING AND WAVE DEVICE

Henry Clay Whittaker, Memphis, Tenn.

Application October 14, 1943, Serial No. 506,239

1 Claim. (Cl. 132—41)

The invention has for an object to present a hair curling device adapted to be produced at extremely low cost from materials which are not critical in the war effort, and which are a stock product in various forms suitable for use in the article and which may be purchased upon the open market.

A further important aim of the invention is to present a hair curling device which may be readily engaged in the hair to produce curls of an extremely natural appearance by simple manipulation.

A further important aim of the invention is to present a curler device which is readily adapted to engagement in the hair and retention while the wearer sleeps, without causing discomfort.

Another important aim is to present a hair curler of novel function in retaining the hair. Another important aim is to present such an article which is readily adapted to be produced and packaged in a compact form, highly advantageous in the retail trade.

A very important aim of the invention is to produce a curler device of such low cost, that it may be readily discarded after a short period of use, and new ones bought and substituted, so that the need for cleaning soiled curlers is obviated, as well as assuring a maximum efficiency which is obtained from newly manufactured goods.

Additional objects, advantages and features of invention reside in the construction, arrangement and combination of parts involved in the device as embodied, as will be more readily understood from the following description and accompanying drawing, wherein

Figure 1 is a plan view of the curler device in its blank form, and as obtained by the user in retail trade.

Figure 2 is a vertical longitudinal section thereof.

Figure 3 is a cross section on the line 3—3 of Figure 1.

Figure 4 is a cross section on the line 4—4 of Figure 1.

Figure 5 is an edge view of the article with a strand of hair wound thereon.

Figure 6 is a similar view showing the article folded to hold the hair as wound.

Figure 7 shows the manner of inserting the point section to retain the article in the wound hair.

Figure 8 shows the point fully inserted so as to hold the wound hair in place on the curler.

Figure 9 is a cross section on the line 9—9 of Figure 8.

Figure 10 is a perspective view of the winding end of the article showing the manner of starting the winding of the hair thereon.

There is illustrated a curler comprising a blank 10 of card-board, which may be approximately of the same material as card-board boxes are made of, although it may be found desirable to have a smooth facing on one or two sides thereof, to avoid the formation of projecting fibers or the like, as well as to permit creasing and bending of the article, as will be described, with a minimum liability of fracture of the material at the line of fold.

The blank is preferably made of a length to afford a standard size curler, so that the device may receive thereon a winding of hair of a suitable diameter. A curl with a winding of approximately one inch in diameter, and a length along the axis of the winding of approximately two inches, is ordinarily desirable, although the size may be varied if desired, or special sizes provided for peculiar requirements as discretion dictates.

The blank 10 is formed with transverse crimps or grooves 11, so as to form the curl-receiving end portion 12 of full length, an intermediate plain portion 13 of approximately the same length as the part 12, and an opposite end portion 14 which may be slightly shorter if desired, and in the present instance, is pointed, having edges 15 inclined from the junction of the point portion 14 with the body portion 13 to a point 16 at the extremity of the blank.

The hair-receiving end 12 is formed with a longitudinal slot 17 extending from near the crease 11 to the extremity of the blank, the sides of the slot being spaced apart approximately one-sixteenth of an inch, and at the extremity of the device being curved divergently. If desired, the longitudinal edges of the blank especially in the part 12, and the edges of the slot 17, may be treated in any suitable way to present a smooth rounded edge, affording a minimum of liability of hooking or breaking of the hair when applied or removed to and from the device.

In practice, I have found a hard glazed card-board to afford a satisfactory material with adequate strength and durability for the use described, and liable in a minimum degree to breakage or damage incident to average use.

In the use of this article, a strand of hair 18 is separated from the rest of the hair upon the head of the user, at the outer part, and the extreme end portion of the strand held taut while the end of the curler is presented thereto in a plane at right angles to the strand, the open end of the slot being slipped onto the strand, so as to

fit thereagainst at each side. The strand being slipped to the inner end portion of the slot, the curler is rotated on its longitudinal axis, so as to wind the hair upon the part 12, from adjacent the crease 11 toward the outer end, in a manner familiar in hair dressing generally. After completion of the winding of the hair as described, the central body portion 13 is bent upon the crease line 11, longitudinally inwardly over the hair, as shown in Figure 4, and then the pointed end portion is curved inwardly, as shown in Figure 5, and inserted within the wound hair and pushed longitudinally into the coil of hair until it lies snugly engaged, as shown in Figure 6, the central portion 13 lying close against the external coiled hair. This operation is repeated with similar strands of hair, until all of the hair to be curled is engaged upon a proper number of the curlers, which may then lie flat against the head

of the wearer, to be retained by hairpins or hair net, or otherwise, as may be found expedient.

I claim:

A hair curler of the character described comprising a blank of sheet material of elongated form, including an end portion longitudinally slotted through the extremity to receive a strand of hair as described, the material of the device being crimped transversely a spaced distance from the inner end of said slot, and having a second transverse crimped portion at a distance from the first crimped portion corresponding to the length of the slotted end portion, a pointed end portion outwardly of the last named crimped part, for the purposes described, the material being adapted to be bent at said crimped portion, for the uses described.

HENRY CLAY WHITTAKER.
